United States Patent Office

Des. 184,034
Patented Dec. 2, 1958

184,034

LACE FABRIC

William N. Woodhouse, White Plains, N. Y., assignor to
New Jersey Lace Corporation, Fairview, N. J.

Application June 3, 1958, Serial No. 51,174

Term of patent 3½ years

(Cl. D47—6)

The figure is a plan view of a lace fabric, showing my new design.

I claim:

The ornamental design for a lace fabric, as shown.
